Primary Examiner — Jack Reickel(74) *Attorney, Agent, or Firm* — McCoy Russell LLP(57) **CLAIM**

The ornamental design for a display screen with graphical user interface, as shown and described.

DESCRIPTION

FIG. 1 is a front view of a display screen with graphical user interface showing a first image in an animation sequence of the graphical user interface according to the claimed design; and,

FIG. 2 is a front view of the display screen with graphical user interface showing a second image in the animation sequence of the graphical user interface.

The dash-dot-dash broken lines showing the display screen and the dash-dash broken lines showing the graphical user interface illustrate portions of the display screen with graphical user interface that form no part of the claimed design.

The appearance of the graphical user interface sequentially transitions between the images shown in FIGS. 1-2. The process or period in which an image transitions to another forms no part of the claimed design.

The oblique hatch shading at the patient position section and set anatomy section in FIG. 2 illustrates contrast in appearance, although no particular color is claimed and any pattern formed by the oblique hatch shading forms no part of the claimed design.
